ATTORNEY.

UNITED STATES PATENT OFFICE.

WALTER J. TIDD, OF SPRINGFIELD, MASSACHUSETTS.

ANTISKID DEVICE.

1,310,221.

Specification of Letters Patent. Patented July 15, 1919.

Application filed April 27, 1918. Serial No. 231,056.

To all whom it may concern:

Be it known that I, WALTER J. TIDD, a citizen of the United States of America, residing at Springfield, in the county of 5 Hampden and Commonwealth of Massachusetts, have invented certain new and useful Improvements in Antiskid Devices, of which the following is a specification.

This invention relates to improvements in 10 devices for preventing the skidding of motor vehicles. It is a well known fact that on slippery streets and pavements, for one reason or another, it is difficult to drive the motor vehicle around a corner without causing 15 the machine to skid dangerously, or while passing by other vehicles on the highway. The invention broadly considered, comprises an attachment that is adapted to be pivotally secured to the rear-axle of the 20 machine. Means is also provided for normally holding the same elevated and away from the ground when it is not in use, and, means for quickly throwing the same into direct contact with the ground or pavement 25 when the machine commences to skid or there is liability or danger of its skidding.

Referring to the drawings:

Figure 1 is a side elevational view of a 30 motor vehicle with a portion of the body part broken away in order to illustrate the attachment of the device to the housing of the rear-axle.

Fig. 2 is an end elevational view of Fig. 1 showing the manner of pivotally connecting 35 the device to the housing of the rear-axle; also illustrating the manner of mounting the wheel.

Figs. 3, 4 and 5 are detail views of modifications of the wheel, which is to be brought 40 into contact with the pavement, the tread portion of the wheel having different shapes or configurations, and

Fig. 6 is a detail enlarged view of the 45 wheel and its mounting, showing the same attached to the housing near its center portion, and

Fig. 7 is a modification showing the brake mechanism.

Referring to the drawings in detail: The 50 body portion of the vehicle is indicated at

1. The housing, which incloses the rear-axle is indicated at 2. 3 designates the wheel which is to be moved into contact with the pavement to prevent the skidding of the machine. The wheel 3 is mounted 55 for free rotation on the shaft 4, which is supported in the hangers 5. These hangers extend upward, as shown, in Figs. 2 and 6, and are pivotally connected to the housing by means of the clamps 6 which are secured to the housing 2 by any suitable means. Their lower ends are provided with depending portions 7 through which the bolts 8 are passed. Extending across and connecting the hanger arms 5 is a rod 9. 60 10 designates a spring of sufficient strength to normally retain the wheel or roller 3 in an elevated position, its lower end being attached to the rod 9 and its upper end to a projection 9' on the plate 11, which is 65 secured to the housing. Rigidly secured to the part 9 is an arm 12 and pivotally attached to the forward end of this arm is a lever 13, the pivot being designated at 14. The lever 13 is attached to the housing or 70 frame work of the machine at 15 and attached to the upper end of the lever 13 is a rod 16, which extends forward, where it terminates near the driver of the vehicle. Its forward end has connected thereto an 80 operating lever 17. Interposed in any suitable manner in the rod 16 is a coiled spring 18, which is for the purpose of providing a buffer device for absorbing or taking up the shocks should the roller 3 strike obstructions or holes in the roadway, otherwise the device might be broken or the operator's hand disengaged from the lever 17. Also attached to the shaft 4 are oppositely located braces 19, which extend in opposite 85 directions and are pivotally secured to the housing 2 in the same manner as already described in connection with the hangers or braces 5; that is to say, by means of the clamps 20, which are mounted on the opposite ends of the housing 2 and their lower ends are formed with depending portions through which pins or bolts 21 are passed, whereby the braces 19 are pivotally connected to the clamps 20. It is understood 90 95 100

that the pins 8, which pivotally attach the braces 5 to the housing 2 and the pins 21, are in alinement with each other, whereby the device as a whole may be normally elevated by means of the spring 10 or lowered by means of the operating lever 17. When the machine begins to skid, the operator pulls rearwardly on the lever 17, causing the roller 3 to be brought forcibly into direct contact with the roadway. This roller may be constructed in different forms as shown, in Figs. 3, 4 and 5, according to the nature of the road on which the machine is to be used. That shown in Fig. 3 is formed with a sharp edge 22, that shown in Fig. 4 is formed with two sharp edges indicated at 23, and that shown in Fig. 5 has a curved edge 24, while that shown in Fig. 6 is formed with two thin edges 24'. By pulling hard on the lever 17 the roller 3 is forced against the pavement with greater pressure and the operator can determine just how forcibly the roller 3 should be pressed against the pavement in order to prevent the machine from dangerously skidding.

It will be noticed that coiled springs 25 are placed on the shaft 4 and on opposite sides of the roller 3, to take up or absorb any lateral forces that may be placed on the wheel 3, otherwise the wheel would be liable to be broken or parts of the mechanism bent, or damaged.

It will be seen that I have provided an anti-friction device that is inexpensive to manufacture and one that can be readily attached to any existing motor vehicle and one that is efficiently operated.

It is to be understood by the term "roller" I do not limit myself to a roller of any particular size, as this term is understood to include the term wheel as being synonymous therewith.

Referring now to the modification shown in Fig. 7, in which a brake construction is shown for the wheel 3, to prevent the wheel from turning, and to prevent the machine from sliding forward, 26 designates a brake shoe, the face of which corresponds in shape to the face of the wheel. That is to say, if the wheel is formed with a V-shaped groove, the shoe is formed with inclined sides to fit the groove. Pivotally attached to the shoe is a bell-crank lever 27, to the inner end of which is pivotally connected the link 28 at the point 29. The bell-crank lever 27 is pivotally connected to the link 12 at the point 27'. Connected to the outer end of the link 28 is a lever 30 at the point 31, and connected to the upper end of the lever 30 is the operating rod 32. The lever 30, it will be noticed, is mounted on the same pivotal point as the lever 13. The forward end of the rod 32 is provided with an operating

hand or foot lever similar to the lever 17, for the purpose of applying the brake-shoe 26 to the wheel 3, to prevent its rotating. If this wheel is constructed of metal and is prevented from rotating, it will serve to prevent the machine from sliding forward as well as side wise. When the operator throws the lever 17 to bring the wheel 3 into contact with the ground, he will, if necessary, apply the brake to the wheel to prevent the machine from sliding forward as well as side-wise.

What I claim is:

1. In a device of the kind described, the combination with the housing of the rear axle of a motor vehicle having a projection, of depending braces pivotally connected to the housing of the rear axle and lying in a plane parallel to the axle housing, so as to swing transversely of said axle housing, a spring device for normally retaining the depending braces in an elevated position away from the roadway, a roller supported at the lower end of the braces for engagement with the roadway and means for moving the device with the roller in a forward direction toward the roadway, said spring device being located between the depending braces and said projection on the housing of the rear axle housing.

2. An attachment for motor vehicles for preventing skidding and comprising two pairs of braces that are pivotally attached to the housing of the rear axle of the chassis of the motor vehicle and which lie in a plane that is parallel to the axle so as to swing transversely of the axle, a roller mounted at the lower end of the braces for engagement with the roadway, an arm on the housing, a spring attached to the arm and to the braces for elevating the roller, manually operated means having a handle for moving the roller into contact with the roadway and against the tension of the elevating spring and comprising a lever pivotally secured to the chassis, a link attached to the roller elevating mechanism one end of which is connected to the link that is attached to the roller elevating mechanism and its other end to a handle on the manually operated means.

3. A device for the purpose described comprising, in combination, two pairs of braces pivotally secured to the housing of the rear axle, a shaft common to said braces, a roller on the shaft for engaging the roadway, spring means for normally retaining the roller in an elevated position, manually operated means for moving the roller into contact with the roadway and against the tension of the spring elevating means, a brake for the roller, said brake being pivotally secured to the roller elevating means, and

means for operating the brake independent of the roller operating means, as described.

4. An anti skidding device for motor vehicles comprising, in combination with the 5 housing of the rear axle, of two sets of braces pivotally connected to the housing, a shaft connecting the lower ends of the braces together, a wheel mounted on the

shaft, compression springs on the shaft and located at the opposite sides of the wheel 10 for absorbing the lateral stresses and shocks, means for retaining the braces and wheel in an elevated position and means for moving the braces and wheel downward.

WALTER J. TIDD.
